G. H. DAVIS

SWITCH MECHANISM

Filed June 14, 1923

UNITED STATES PATENT OFFICE.

GEORGE HENRY DAVIS, OF RICHMOND, VIRGINIA.

SWITCH MECHANISM.

Application filed June 14, 1923. Serial No. 645,384.

This invention has for its object to provide a certain new and useful means for controlling the operation of a stop, start, back and turn traffic signal for use on automobiles and motor vehicles; and it especially has for its object to provide a lever operated means mechanically acting to set the signal to either of its positions and at the same time permit control of the sounding of a horn or other audible signal and the illumination of an electric light in cooperation with the traffic signal at the will of the operator.

More specifically the invention resides in the provision of a signal setting switch device adapted to be mounted on the steering wheel post of a motor vehicle and which includes a signal actuating shaft with the operating lever that also functions as the circuit closing device for the audible and light signals.

The present application is a continuation in part of my patent issued Jan. 15, 1924, Pat. No. 1,480,816.

In its more detailed nature, the invention includes those novel details of construction, combination and arrangement of parts, all of which will be first fully described, then be specifically pointed out in the appended claims, and illustrated in the accompanying drawing, in which:—

Figure 1 is a top plan view of the signal actuating mechanism switch.

Figure 2 is a horizontal section and plan view, the upper plate being removed.

Figure 3 is an inverted plan view of the removed upper plate.

Figure 4 is a central vertical longitudinal section of the mechanism shown in Figure 1.

Figure 5 is a detailed vertical section on the line 5—5 on Figure 1.

Figure 6 is a diagrammatic view illustrating the circuit arrangements and connections between the traffic signal and the operating switch.

Figure 7 is a diagrammatical view of the mechanical connections between the traffic signal drum and the operating shaft of the actuating mechanism.

In the drawing, in which like numerals of reference indicate like parts in all of the figures, 1 represents the lower plate of the actuating mechanism, the same being provided with ears 2 by means of which it may be secured to the clamp ears 3 of the clamp

4 which is formed to cooperate with the lower plate 1 and the upper plate 22 to provide an opening 5 for the steering post 53 of the vehicle on which it may be clamped by suitable screws or bolts (not shown) 60 passed through the ears 23—23.

The plate 1 carries terminal posts 6 and 7 which are countersunk below the top face of the plate 1 (see Figure 5) and to which the terminal wires 51 and 52 from the light 47 and audible signal 46 are connected, the other terminals of those signals being connected by wires 50 to one side of the battery 48, the other side of which is connected by a wire 49 to a terminal post 21 carried by 70 the conductor plate 16, which is countersunk flush with the top face of the plate 1. It should be understood that the plate 1 is made of suitable insulating material as wood, for example. The plate 1 is bored at 85 75 8 and bushed at 9 to form a bearing for the shaft 10 which is held in place by collars 11 and carries a head 12 with ears 13 between which the operating lever is hinged at 14.

The plate 16 carries four upstanding contact posts 17, 18, 19 and 20, respectively arranged in the arc of a circle having the shaft 10 as its center.

22 is the upper plate which is also made of insulating material and is bored at 54 and bushed at 24 to form a bearing for the shaft 10. This plate 22 carries two conductor plates 25 having tapped enlargements 27 for the screws 28, the latter having wings 29 by which they may be turned down or up 90 to contact or not contact the terminal posts 6 and 7 for purposes presently explained. The plates 25 also have tapped enlargements 30 for the screw posts 31 on which the contact plate 32 is mounted for movement 95 up and down against the tension of coil springs 34 on the screw posts 31. A coil spring 35 is also provided midway the ends of the plate 32 to press it up and keep it in contact with the contact finger 38 of the operating lever 15. The lever 15 also has a contact finger 37 to cooperate with the contact posts 17 to 20, inclusive, and to engage a dummy or dead contact post 36 in the mid-position of the lever, if desired. The post 100 105 36 is secured in the upper plate 2.

The contact plate 32 is provided with stops 33 to limit the sidewise movement of the lever 38.

Screws 26 may be provided for securing 110

the plates 25 to the plate 22 and the plates 1 and 22 may be secured together by screws 39, as indicated.

The upper plate 22 has holes 40 to permit the contact posts 17 to 20, inclusive, to project up into cooperative relation to the contact finger 37 similarly to the position of the post 36.

Mounted on the shaft 10, at a suitable place, is a rocking lever 41, the ends of which are connected to the ends of a wire 44 which passes through a duct 42 and around the sheave of the traffic signal drum 43 (see my original application, etc., for details of construction thereof) whereby when the lever 15 is moved from the position shown in Figure 1 right or left, as the case may be, the drum 43 will be correspondingly turned, to bring the proper visible signal into position for view.

In the practical operation of my invention when it is desired to turn right or left, back or stop, the operator moves the lever 15 to the left or right, as the case may be, in alignment with one or another of the contact posts 17 to 20, inclusive, and at the same time, by pressing down on the lever 15, he closes the circuit from plate 32 via fingers 38-37 to the proper contact posts 17, 18, 19 or 20 to permit energization of the horn 46 and light 47, assuming, of course, that the screws 28 are screwed down into contact with the terminal post 6. In the day time, when the light 47 is not to be used, the screw 28 at the left in Figure 1 is unscrewed from contact with its terminal post 6, thus breaking the light circuit. If it is desired to omit the horn operation the other screw 28 is unscrewed to break the circuit.

From the foregoing, it will be seen that with a single turn, the user of my invention can set the traffic signal at the desired indication, and at the same time, and with practically the same operation, can, at will, cause the sounding of the horn and or the lighting of the illuminating instrumentality 47. In other words, it only requires the one hand of the operator to effect the desired signal indication in the traffic signal and sound the horn or light the light, or both, as the case may be.

From the foregoing, taken in connection with the accompanying drawing, it is thought the complete construction, operation and advantages of my invention will be readily understood by those skilled in the art.

What I claim is:—

1. A switch unit comprising a base consisting of two insulating sections placed one on top of the other, a common conductor

plate on the top of the bottom section, a series of contacts on the top section with portions to engage said common conductor plate when said base sections are assembled, an arcuate contact plate, spring means for mounting said arcuate contact plate on top of said top base section, lever stops at the ends of said arcuate plate, a shaft journalled in a bearing in said base, and an articulatable lever secured to said shaft to turn it on its axis, said lever having a portion adapted to be moved up and down and having a contact lug in engagement with the top of said arcuate plate and another contact lug adapted to cooperate with said series of contacts.

2. A switch unit comprising a base consisting of two insulating sections placed one on top of the other, a common conductor plate on the top of the bottom section, a series of contacts on the top section with portions to engage said common conductor plate when said base sections are assembled, an arcuate contact plate, spring means for mounting said arcuate contact plate on top of said top base section, lever stops at the ends of said arcuate plate, a shaft journalled in a bearing in said base, an articulatable lever secured to said shaft to turn it on its axis, said lever having a portion adapted to be moved up and down and having a contact lug in engagement with the top of said arcuate plate and another contact lug adapted to cooperate with said series of contacts, a circuit terminal mounted on the bottom base section, a circuit terminal mounted on the top base section, said circuit terminal of the top base section being connected to said arcuate plate and a contact make and break screw carried by said circuit terminal of the top base section for cooperation with said circuit terminal of the bottom base section for the purposes specified.

3. A switch comprising a base, a shaft journalled in said base, a lever mounted thereon said lever adapted to be moved from right to left with said shaft as an axis, a set of contact posts on the base beneath said lever, a contact plate yieldably mounted on the base to engage said lever, means for pressing said plate to hold said lever normally out of engagement with said contact posts, circuit terminal posts on said base, means connecting one of said terminal posts with each of said contact posts, and another means for connecting the other terminal post with said contact plate, said other means including circuit opening and closing elements mounted on the base independently of the lever.

GEORGE HENRY DAVIS.
